ROLL SEAL

Kristian Skivesen, Flourtown, Pa., assignor to
 Selas Corporation of America, Philadelphia,
 Pa., a corporation of Pennsylvania

Application May 18, 1950, Serial No. 162,760

13 Claims. (Cl. 263—3)

1

The present invention relates to the heat treatment of sheet metal, and more particularly to a roll seal that can be used at the entrance or exit of a treating chamber to keep the chamber closed so that a desired atmosphere can be maintained therein.

In the treatment of strip material such as the continuous annealing of strip steel, for example, the strip is moved through a furnace chamber where it is heated, often under a special atmosphere. From the furnace chamber the strip is passed through a cooling chamber that is usually supplied with a neutral atmosphere, and from there to a point of use or storage. In both the furnace and the cooling chamber it is necessary to provide a seal at the exit and entrance to maintain the atmosphere in the treating space. It is also necessary that this seal be so designed that the strip can move into or out of the treating chamber without any retarding effect thereon and without marring its surface, even though the thickness of the strip may vary from time to time.

It is an object of the present invention to provide a roll seal to be used in the treatment of strip materials to seal the entrance or exit of a treating chamber. It is a further object of the invention to provide a seal of the type described in which the rolls and the seals cooperating therewith are mounted for movement in such a way that irregularities in the thickness of the strip may be compensated for without changing the path of the strip.

In the seal of the present invention there are provided a pair of rolls between which the strip passes. These rolls are mounted for simultaneous movement toward and from each other, but are biased normally in a direction to grasp the strip between them. Between the rolls and the treating chamber with which they are used are a series of sealing members to close the space between the chamber and the rolls in a substantially gas-tight manner.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described a preferred embodiment of the invention.

In the drawings:

Figure 1 is a side view of a portion of the apparatus showing the sealing arrangement;

2

Figure 2 is a view taken on line 2—2 of Figure 1 with a portion of the furnace shown in section;

Figure 3 is a view taken on line 3—3 of Figure 5 with certain parts shown in section;

Figure 4 is a view, partly in section, of a modified form of the invention; and

Figure 5 is a view, partly in section, taken from the right of Figure 4.

The roll seal of the present invention may be used between any two chambers or at the entrance or exit of a chamber through which a strip passes which chambers are to be sealed from each other or the atmosphere. In this application the seal is disclosed by way of example as being used between a holding furnace zone and a cooling chamber in a strip annealing apparatus of the type generally shown and described in the application of Frederic O. Hess, Serial No. 48,203, filed September 8, 1948.

Referring to the drawings and Figures 1 and 2, in particular, there is shown the holding furnace section 1, the lower end of which is closed by the seal 2 through which the strip passes between the furnace and a closed cooling chamber or duct 3. The furnace, shown herein, comprises the holding zone of a continuous annealing line, and is so designed that it will maintain the temperature of a strip S at the annealing temperature prior to the time it is being passed into a cooling zone where controlled cooling can take place. The furnace is of the radiant panel type and includes two panels 4 and 5 which are mounted for movement toward and from each other. To this end there are provided tracks 6 upon which wheels, shown diagrammatically at 7, ride as the furnace sections are moved toward and from each other. The details of the furnace construction and the manner of moving these panels form no part of the present invention so that it is not necessary to describe the construction therefor. The lower portion of each of the furnace panels consists of a casting 8 or 9, respectively, upon which the remainder of the furnace is built. The furnaces are built in accordance with usual furnace construction of refractory brick that is backed up by sheet metal work 11. Each of the panels also includes a number of radiant type burners formed of refractory material, which are directed toward the strip as it is moved through the furnace chamber. These burners are preferably of the type shown in Hess Patent 2,215,079, granted September 17, 1940, and include blocks 12, each of which is provided with a cup-shaped opening 13 into the base of which is disposed a distributor member 14. A com-

50
 45

 35
 30
 25
 20
 15

combustible fuel mixture is supplied through pipe 15 to the distributor from which it is discharged as a plurality of small jets which burn along the surface of the cup 13 to heat the same to incandescence and thereby direct radiant heat against the strip. The supply of fuel to each of the burners is controlled in any suitable manner as by a valve indicated herein at 16.

Below the furnace and the seal is the cooling chamber shown as a duct 3 into which the strip is fed after it has been heated. This duct may be insulated or not, depending upon the cooling requirements of the particular installation with which it is used. In any event, the upper end of the duct is fastened in pressure-tight relation to a rectangular casting 17 that surrounds the strip as it is moving downwardly, as shown in the drawings. This casting, as indicated best in Figure 3, is hollow so that a cooling fluid, such as water, may be circulated through it.

The roll seal comprises a pair of rolls between which the strip moves, and sealing members between the rolls and the furnace and between the rolls and casting 17. These members are so arranged that a substantially gas-tight seal is obtained at the exit of the furnace and at the entrance of the cooling duct. This seal serves to prevent undesirable air from entering the furnace chamber and to prevent the escape of the atmosphere supplied to the cooling duct in which the strip is cooled. The seal includes a pair of heat resisting alloy rolls 18 and 19 which are mounted respectively upon shafts 21 and 22 that are journaled in bearings 23 and 24. The bearings are mounted for movement toward and from each other so that the rolls can move toward and from each other to allow for inequalities in the thickness of the strip. The arrangement is such, however, that the rolls are at all times biased toward each other into engagement with the strip. It is noted that the mounting of each roll and the seal members between each roll and the furnace and casting 17 respectively, are duplicates. Therefore, the same reference numerals will be used for the duplicate parts. Each of the bearings 23 and 24 has a plate 25 attached to it, which plate is in turn securely bolted to a plate 26 formed on the upper part of a sleeve 27. Each sleeve has an arm 28 projecting downwardly therefrom. Each of the sleeves 27 is journaled for oscillating movement around a shaft 29 that is in turn journaled for rotation in rigidly mounted bearings 31. The bearings are attached to the framework 32 of the apparatus. It will be seen from an inspection of the drawing that the bearings for supporting the roll shafts and the extensions 28 on the lower ends of the sleeves 27 in effect form levers which pivot around the shafts 29. The lower ends of the arms 28 are connected by a pair of links 33 of such a length that they extend upwardly at an angle to the horizontal. The inner ends of these links are pivoted together and pivoted to a slider 34 that is guided for vertical movement in guides 35 attached to the frame. It will be seen that a downward movement of the slider will cause the links 33 to act similar to a toggle joint to move the lower ends of arms 28 away from each other, to in turn move the surfaces of the roll 18 and 19 into engagement with each other or with a strip that is passing between them. The slider 34 is biased downwardly at all times by means of weights 37 that are attached to the slider by a rod 36. Only one end of the rolls and the mounting therefor have been shown in Figure 1 of the drawing, since the other

end of the rolls and the mounting means therefor is exactly the same.

In some cases the rolls can be driven by the strip. In most cases, however, it is desirable to drive the rolls so that they will help to move the strip through its path of travel. The mounting arrangement of the rolls disclosed herein is admirably suited for a positive driving arrangement and provision may be made therefor at either end of the rolls. As disclosed herein, the rolls are positively driven by a motor 38 that is mounted on the framework 32 of the apparatus. This motor is connected through a coupling 39 with a shaft 29, the right one in Figure 2 for example, to drive the same. This shaft 29, which rotates around a fixed axis, has a gear 41 on it that meshes with a gear 42 on shaft 22 to which roll 19 is attached. Therefore, when the motor is driven, roll 19 will also be driven. A similar gear 20 is provided for rotating roll 18. For this purpose there is provided a gear on the left shaft 29 in Figure 2 which meshes with the gear 41, and there is provided a gear on the shaft 21 that is driven by the gear on the left shaft 29. It will be clear 25 that the two driving gears on the shafts 29 can mesh with the gears on shafts 21 and 22 even though said shafts are oscillated around shafts 29. This arrangement permits a positive drive to each of the roll shafts at any position of the latter even though they may be moved toward and from each other. It is noted that shafts 21 and 22 are hollow and they may be water-cooled if desired by supplying water to each through a supply pipe 44. These pipes should be flexible enough 30 to compensate for the movement of the shafts.

Sealing means are provided between the rolls and the furnace panels to prevent the inflow of excess air to the furnace chamber and also to prevent the loss of heat. As seen in the left portion of Figure 3, the casting 8 is curved downwardly with a relatively great clearance between the bottom part of this casting and the surface of roll 18. The casting 8 is made in a similar manner. There is provided sealing means which extends between the lower portion of the casting and axially along the surface of the roll. This sealing means takes the form of a metal strip and is shown at 46 in the drawing. A gasket 47 is placed between the casting and the strip itself. The mounting means for this sealing strip includes a vertically disposed piece 48 on the casting to which is bolted an angle iron 49 upon which the sealing strip rests and slides. The strip is biased at all times into engagement with the surface of the roll by a rod 51 whose inner end engages the back of the strip and whose outer end is engaged by the vertically extending portion of a bell crank lever 52 that is pivoted at 53. A weight 54 biases lever 52 in a counter-clockwise direction to force the sealing strip against the surface of the roll.

As was mentioned above, the furnace panels may be moved toward and from each other. As the furnace panel 4, for example, is moved to the left away from the roll, the weight 54 will continue to bias the sealing strip toward the roll. This movement toward the roll, however, is limited by a pin 50 extending through the angle 49, which pin will engage a portion of the sealing strip to limit its outward movement. Therefore, the sealing strip will not be dislodged from its supporting means as the panel upon which it is mounted is moved away from the roll. Each of the sealing strips 46 extending axially along the 55 rolls is formed of a number of individual sections.

These sections engage each other with a tongue and groove joint 55 as is indicated in Figure 1 of the drawing. When the furnace is heated up all of the parts in contact therewith will also be heated. The tongue and groove joints between the sections of the sealing strips permit expansion of the sealing strips to take place without forcing them beyond the edges of the furnace.

There is also provided a substantially triangular sealing member 56 which extends into the crevice or nip between the rolls 18 and 19 to close off the gap that is formed between the sides of the furnace at this point. As best seen in Figure 2 of the drawing, this piece extends on both sides of the center of the furnace to overlap the central portion of both of the furnace sections 4 and 5. The sealing member 56 is pivoted at 57 on the furnace panel 5 and is provided with a downwardly extending arm 58. As the furnace panels are moved away from each other panel 5 will be moved to the right in Figure 2 of the drawing. During this movement sealing member 56 will ride up along the surface of roll 19 causing the arm 58 to move clockwise downwardly. Just as the sealing member is riding off the surface of the roll the lower end of arm 58 will be engaged by a pin 59 that projects outwardly into the path thereof from some stationary member such as the track 6. This pin will hold the sealing member 56 in its clockwise position until such time as the panels are moved toward each other again. Because of the cooperation between arm 58 and pin 59 the sealing member will be held in its clockwise position and will be ready to return to the position between the rolls when the panels are moved together. Referring to Figure 1, it will be seen that the rolls 18 and 19 are longer than the width of the furnace. This means that the sealing member 56 can bear against the surface of the rolls rather than against the ends thereof. By having this member bear against the surface of the rolls a very accurate seal can be obtained between the rolls and the end of the furnace.

The spaces which extend circumferentially of the rolls between the sides of member 56 and the tops of sealing strips 46 are closed by arcuate members 45. Each of these members, as shown in Figures 2 and 3, is attached to the end of one of the strips 46 so that it will move back and forth with the strip as the rolls move.

There is also provided a seal between the rolls 18 and 19 and the casting 17 at the entrance of the cooling duct 3. These seals serve the purpose of keeping the upper end of the cooling duct 3 closed with respect to the air so that any particular atmosphere in this duct will be maintained. As best shown in Figures 1 and 3, the seal includes sealing strips 61 extending axially of the rolls and each of which is pressed against both one of the rolls and a side of the casting 17. Each sealing strip is biased upwardly against the roll by a rod 62 that is guided for movement by guides 63 on the outside of the casting. The lower end of rod 62 is engaged by the inner end of a lever 64 that is pivoted at 65. This lever is biased in a direction to move the rod upwardly by a weight 66 attached to the outer end thereof. The sealing strip 61 is biased inwardly against the side of the casting by a lever 67 that is pivoted at 68. This lever in turn is biased in a clockwise direction as shown in Figure 3 by a lever 69 that has a push plate 71 on the end thereof. The lever 69 is moved around its pivot 72 by a weight 73.

on the outer end thereof. This sealing strip 61 is also made in sections as was the sealing strip 46. These sections from end to end engage each other with a tongue and groove connection as is shown at 85 in the drawing. Sealing means 61 are used both between the left side of the casting 17 and roll 18 as well as between the right side of the casting and roll 19.

A sealing member is also used to close the gap between the cavity or nip of the rolls and the end of the casting 17. This member takes the form of a substantially triangular shaped piece 74 that is forced upwardly into the nip of the rolls by the upper end of a rod 75. The lower end of this rod has force applied to it by the inner end of a lever 76 that is pivoted at 77, and whose outer end has a weight 78 attached to it. The sealing member 74 is biased against the end of casting 17 by a lever 79 that is pivoted at 81. This lever in turn is moved in a clockwise direction in Figure 1 by a second lever 82 that is pivoted at 83 and which is biased in a counter-clockwise direction by a weight 84. From the above description it will be seen that sealing strips extend all the way around the casting 17 between this casting and the rolls to completely close off any opening through which the atmosphere in the cooling duct 3 could readily escape.

Casting 17 to which the upper end of duct 3 is attached is shorter than the rolls. This casting may be held in position by any suitable means. As shown herein, however, there are provided supporting structural members 86 extending between the frame 32 and each corner of the casting to hold this casting in position. Similar structural members extend between the frame on the other side of the apparatus and the other end of this casting.

The sealing means that has been described above is used between the furnace and the entrance of the cooling duct. At this location there is a good deal of heat in the strip and the furnace that will be transferred to the sealing means. For this reason weights are necessary in order to keep the various sealing strips against the rollers. In other locations such as the exit of the cooling tower where the strip is at a relatively low temperature springs can be used in place of weights to keep the sealing means against the rolls and the duct in order to maintain the atmosphere in the duct. Such a sealing means is shown in Figures 4 and 5.

As disclosed in these figures, there are rolls 18a and 19a that are mounted on shafts 21a and 22a respectively. These rolls are supported by structure similar to that described above for supporting rolls 18 and 19. A driving means may also be used for these rolls if it is so desired. Referring to the figures it will be seen that the duct 3 has fastened to it a rectangular frame 87, the lower edge of which terminates close to the rolls. As shown in this figure, there are provided sealing strips 88 extending axially of the rolls and abutting the sides of the frame 87. These strips are pressed into engagement with the rolls by means of springs 89, the upper ends of which are received in cups 91. The cups are mounted on adjustable supports 92 that are in turn fastened to a flange 93 extending perpendicularly to the frame and around the same. The sealing strips 88 are forced against the side of the frame by springs 94. The outer ends of these springs are received in cups 95 that are

attached to supports 96, also fastened to the flange 93.

The space between the ends of the frame 87 and the rolls is closed by a sealing member 97 which is substantially triangular in shape and which extends downwardly into the crevice or nip of the rolls. This member is biased downwardly into engagement with the rolls by a spring 98 whose upper end is received in a cup 99. The cup is attached to the flange 93 by an adjustable support 101. The sealing member 97 is forced inwardly against the end of the frame 87 by springs 102. The outer end of these springs are received in a cup 103 which is fastened to a support 104; this in turn is mounted on the flange 93. It will, therefore, be seen that the space between the entire lower end of the frame 87 and the rolls 18a and 19a is closed by sealing members which are biased against both the frame and the rolls.

From the above description it will be seen that I have provided a roll seal between two chambers through which a strip to be treated is travelling. This seal is so made that there is substantially no leakage between the chambers or between the chambers and the atmosphere. The rolls are so mounted that they will move equal amounts from a predetermined central position as irregularities in the strip pass between them. Therefore, the strip will always be guided in a straight path as it is passing from one chamber to the other regardless of any irregularities in the thickness thereof. This construction is particularly advantageous where a lap joint occurs between the end of one strip and the beginning of a second strip that is attached thereto. The mounting means for the rollers also permits a positive drive to be applied thereto with a minimum of trouble. Because both of the rolls move around stationary axes it is easy to drive the rolls through gearing that is fixed relative to the said axes.

The sealing means that is provided between the rolls and the ends of the chambers through which the strip travels is such that practically no leakage can occur either axially of the rolls or at the point where the rolls meet. The sealing strips used between the rolls and the ends of the chambers are biased at all times into engagement with both the rolls and the chamber so that any expansion thereof will occur as a result of heating of the strip or the apparatus can readily be taken up without in any way affecting the ability of the apparatus to close the space between the chamber and the rolls. Furthermore, the sealing means disclosed between the rolls and the sides of furnace panels is such that it will automatically assume its sealing position after the furnace panels have been moved from their inoperative position to the operative position shown in the drawings. It is particularly advantageous to have the rolls longer than the chambers since a better seal can be obtained between the chambers and the surface of the rolls than can possibly be obtained between the chambers and the end of the rollers where any expansion of either part will take place due to heating and cooling of the apparatus.

While in accordance with the provisions of the Statutes, I have illustrated and described the best form of embodiment of my invention now known to me it will be apparent to those skilled in the art that changes may be made in the form of the apparatus disclosed without departing from the spirit and scope of the invention, as

set forth in the appended claims, and that in some cases certain features of my invention may be used to advantage without a corresponding use of other features.

What is claimed is:

1. The combination of structure forming a first treating chamber, structure forming a second treating chamber, the entrance of the second chamber adjoining the exit of the first, and means to seal one of said chambers from the other comprising a pair of rolls, means to mount said rolls for rotation between said chambers in the exit of the first and the entrance of the second, said mounting means including a pivotal support located adjacent to said structures for each of said rolls whereby said rolls can move bodily toward and from each other, sealing means between said first mentioned structure and each of said rolls, and sealing means between said second mentioned structure and each of said rolls.

2. The combination of claim 1 including means to bias each of said sealing means against the structure with which it is associated and the rolls whereby the sealing means will engage both the said structures and the rolls at all times.

3. In annealing apparatus for strip material, the combination of structure forming a heating chamber having an opening through which the strip leaves the chamber, structure forming a cooling chamber having an opening through which strip enters said chamber, the openings in said chambers being aligned with each other in the direction of movement of the strip, a pair of rolls, means to mount said rolls for rotation between the openings of said two chambers so that the strip passing from said heating chamber will go between said rolls and into said cooling chamber, a heat seal engaging said first mentioned structure around its opening and said rolls to close the space between said heating chamber and said rolls, and a gas seal engaging second mentioned structure around its opening and said rolls to close the space between said rolls and said cooling chamber opening.

4. In apparatus of the class described, the combination of structure forming a treating chamber for strip material and having an opening therein through which the strip passes, a pair of rolls, means to mount said rolls adjacent to said opening and across the same and for bodily movement toward and away from each other, the surfaces of said rolls forming a crevice between them, sealing means on said structure and extending axially of said rolls, means to bias said sealing means into engagement with said rolls, sealing means extending transversely of said rolls and into the crevice between them, and means to mount said last-mentioned means on said structure for movement into engagement with said rolls, said first-mentioned and second-mentioned sealing means serving to close the spaces between that structure and said rolls to seal the opening of the chamber.

5. In apparatus of the class described, the combination of structure forming a treating chamber for strip material and having an opening in the end thereof through which the strip passes, a pair of sealing rollers extending across said opening and adjacent thereto, the strip passing between them, means to mount said rollers for rotation and for bodily movement toward and from each other, means to bias said rollers toward each other to grip the strip between them,

the space between the surfaces of said rolls forming a crevice, a plurality of sealing elements, means to mount said elements to said structure extending in a direction parallel to the axes of said rollers, means to bias said elements into engagement with the surfaces of said rollers to close the space between said structure and the surface of said rolls, sealing means to extend into the crevice between said rolls, means to mount said sealing means on said structure for movement towards and away from said rolls, and means to bias said last mentioned sealing means into engagement with said rolls to close the space between said structure and the crevice between the rolls.

6. In combination, structure forming a treating chamber for strip material having an opening at one end, a pair of rolls between which said strip passes, means to mount said rolls across and adjacent to the opening of said chamber to close the same, said mounting means comprising a pair of levers, means to mount said levers substantially parallel to each other with each lever pivoted for movement around a point intermediate its ends, means to journal a roll on one end of each lever, means to bias the opposite ends of the levers apart to thereby move the rolls together, and means to seal the space between the rolls and said structure.

7. The combination of claim 6 in which said sealing means includes members extending parallel to the axis of each roll outside of said structure, and means to bias said members against the surface of said rolls and against the outside of said structure.

8. In structure of the class described, the combination of a rectangular casting through which strip material is to pass, means to close the top of said casting comprising a pair of rolls adjacent thereto between which the strip passes, each roll being longer than said casting, means to mount said rolls for bodily movement toward and from each other including levers upon which each roll is mounted, means to bias the levers supporting each roll in a direction normally to maintain said rollers in engagement with each other, the surfaces of said rolls forming a crevice between them, sealing strips extending lengthwise of said casting and each roll, means to bias each of said sealing strips against a side of said casting, means to bias each of said strips against the surface of a roll, a sealing means at each end of said casting and extending into the crevice between the rolls, means to bias each sealing means into engagement with an end of said casting, and means to bias each sealing means into engagement with said roll.

9. In apparatus of the class described adapted to close the end of a treating chamber, the combination of a pair of elongated rolls mounted across the end of said chamber and between which a strip of material is passed, a plurality of levers, means to journal an end of each roll upon one end of each lever, means to support each lever intermediate its ends for pivoted movement and with the rolls adjacent to and parallel to each other, means to bias said levers in a direction to force said rolls together and means to rotate said rolls in unison in opposite directions including first gears coaxial with and attached to each roll, second gears meshing with

said first gears and with each other, said second gears being mounted for rotation coaxially with the pivots of a lever supporting one end of each roll, and motor means to drive positively one of said second gears.

10. The combination of claim 9 including structure forming a treating chamber for the strip above the rolls, structure forming a second treating chamber for the strip below said rolls, the strip passing from one chamber between the rolls to the other chamber, and sealing means to close the space between the rolls and each chamber.

11. In apparatus of the class described, the combination of structure forming a chamber 15 through which a strip to be treated is passed, said structure terminating in a portion substantially rectangular in shape and having elongated side walls and joining end walls, a pair of rolls longer than said side walls, means to mount said rolls 20 parallel to each other and parallel to said side walls adjacent to the end of said chamber, sealing means extending parallel to each side wall and between each side wall and the surface of the roll nearest the same, means to bias said sealing means into engagement with said side walls, means to bias said sealing means into engagement with said rolls, sealing members parallel to said end walls and shaped to engage the adjacent surfaces of said rolls, means to bias one 25 of said sealing members into engagement with each of said end walls, and means to bias said members toward said rolls, said sealing means and sealing members serving to close the space between the structure and the rolls to form a 30 substantially gas tight seal between them.

12. The combination of claim 11 in which said mounting means includes means to support each roll for rotation and for bodily movement toward and from the other, and means to bias said 35 rolls toward each other at all times, the biasing means for said sealing strips giving as said rolls move bodily relative to each other.

13. In combination, structure forming a chamber having an opening at the end thereof through 40 which a strip of material to be treated passes, a pair of rollers extending lengthwise in front of said opening substantially to close the same and between which the strip passes, means to support said rollers including a plurality of levers, 45 means to journal one end of each roller for rotation upon one end of each lever, means to pivot each of said levers at a point between its ends for movement around an axis parallel to the axes of said rolls, linkage means connecting the 50 levers at each end of the rolls for simultaneous movement in opposite directions, means to bias said levers in a direction to move said rolls toward each other, and sealing means extending 55 between all sides of the opening of said structure and the surfaces of said rolls.
